(57) **CLAIM**

The ornamental design for a table, as shown and described.

DESCRIPTION

FIG. 1 is a perspective view of a table with stools showing my new design;

FIG. 2 is a perspective view of the table thereof;

FIG. 3 is a front elevation view of the table thereof;

FIG. 4 is a rear elevation view of the table thereof;

FIG. 5 is a left-side elevation view of the table thereof;

FIG. 6 is a right-side elevation view of the table thereof;

FIG. 7 is a top plan view of the table thereof; and,

FIG. 8 is a rear plan view of the table thereof.

The broken lines shown in FIG. 1 form no part of the claimed design.
